[57] **CLAIM**

The ornamental design for shower curtain holder, as shown and described.

DESCRIPTION

FIG. 1 is a perspective view of a shower curtain holder showing my new design;

FIG. 2 is a top plan view thereof;

FIG. 3 is a side elevational view thereof; and

FIG. 4 is an end elevational view thereof.

The side and end opposite to those shown in FIGS. 3 and 4 are substantially mirror images thereof, and the bottom of the holder is substantially flat and unornamented.
